UNITED STATES PATENT OFFICE.

CHARLES F. MOSELEY, OF BERGEN, NEW YORK.

TAG.

SPECIFICATION forming part of Letters Patent No. 428,314, dated May 20, 1890.

Application filed January 30, 1890, Serial No. 338,667. (No model.)

To all whom it may concern:

Be it known that I, CHARLES F. MOSELEY, of Bergen, in the county of Genesee and State of New York, have invented a new and useful Improvement in Tags, which improvement is fully set forth in the following specification, and shown in the accompanying drawings.

The object of my invention is to produce an improved folding tag for use on express, freight, or other packages, the tag being designed to have written or printed upon its inwardly-turned faces or otherwise contain items of information relating to the shipment, advertisements, or other matter.

15 The invention consists in certain novelties in the matter of the construction of the tag, which are hereinafter fully described, and more particularly pointed out in the claims.

Referring to the drawings, Figure 1 shows 20 the tag in one form folded, and Fig. 2 the same opened out. Fig. 3 shows a modified form of the tag, and Fig. 4 the same opened out. Fig. 5 shows still another simple modification in the form of the tag.

25 Referring to the parts, A B are the two sides of the tag, which fold together on a longitudinal line *a*, somewhat like the cover of a book. The side A is formed with a slit *b*, and the side B is formed with a tongue *c*, to 30 enter said slit when the tag is folded, as shown in Fig. 1. The sides are each formed with a folding fly *d*, which may be folded down upon and gummed to the side, as indicated by dotted lines on the side A in Figs. 35 2 and 4, or these flies may be left unfolded, as shown in full lines on the side B, and turned down when the fastening-string is passed through the holes *e*, formed to receive the string. The use of the fly is, as in other 40 tags, to re-enforce and strengthen the material about the holes for the string.

One of the principal novel features of my invention consists in forming orifices *f* in the side B, through which the side A may be 45 seen when the tag is folded, and forming upon the side A opposite these orifices letters forming a word, which will lead the receiver of the package to open or unfold the tag and read the contents. For instance, the word 50 "Open," may be formed upon the side A with a hole *f* in the side B opposite each letter, so

that the word may be read through these holes when the tag is folded and attached to the package, as shown in Fig. 5, this being an inducement for the observer to open the tag 55 and read the contents.

Instead of letters or colors, any characters or figures calculated to attract attention may be formed or stamped upon the side A, to be seen through the openings *f*, my object in 60 this feature of the invention being to exhibit something through the openings *f* to excite the curiosity of persons seeing the tag for the purpose of causing them to open the tag and read the advertisement or other matter 65 within.

Either form of the tag may also be provided with lips *h*, partially severed from the respective sides A B, for the purpose of holding a detachable sheet C, upon which may be 70 written or printed any matter that may be desired, in addition to the advertisement or other matter printed directly upon the inwardly-turned faces of the tag itself.

This tag may be folded either way upon the 75 line *a*, so as to bring either of the faces of the sides A B outward, and the tongue *c* and slit *b* may be made at the sides of the parts A B, instead of at the ends, as shown.

What I claim as my invention is— 80
1. A folded tag capable of being unfolded or opened, formed of a sheet folded in two parallel sides or parts A B, having a tongue *c*, and slit *b* for the tongue, with letters or words formed on one of said sides or parts, 85 and opposing holes formed through the other side or part to uncover or render visible said letters or words, substantially as and for the purpose specified.

2. A folding tag formed with tongue *c* and 90 slit *b*, and further formed with holding-lips *h*, said tag having orifices *f* formed in one of its sides, and opposing colors or characters visible through said orifices when the tag is folded, substantially as described. 95

In witness whereof I have hereunto set my hand, this 18th day of January, 1889, in the presence of two subscribing witnesses.

CHARLES F. MOSELEY.
